(57) **CLAIM**

The ornamental design for a computer armrest, as shown and described.

DESCRIPTION

FIG. 1 is a top perspective view of a computer armrest showing my new design;

FIG. 2 is a bottom perspective view thereof;

FIG. 3 is a left side elevational view thereof;

FIG. 4 is a right side elevational view thereof;

FIG. 5 is a bottom plan view thereof;

FIG. 6 is a top plan view thereof; and,

FIG. 7 is a top perspective view thereof. The broken lines of platform and arrangement of the armrest are for illustrative purposes only and form no part of the claimed design.
